UNITED STATES PATENT OFFICE.

REUBEN BROOKS AND WILLIAM N. LE PAGE, OF ROCKPORT, MASS.

EVAPORATING APPARATUS.

SPECIFICATION forming part of Letters Patent No. 243,686, dated July 5, 1881.

Application filed April 9, 1881. (No model.)

To all whom it may concern:

Be it known that we, REUBEN BROOKS and WILLIAM N. LE PAGE, of Rockport, in the county of Essex and State of Massachusetts, 5 have invented certain new and useful Improvements in Evaporating Apparatus; and we do hereby declare the following to be a full, clear, and exact description of the invention, such as will enable others skilled in the art to which it pertains to make and use it, reference being had to the accompanying drawings, which form part of this specification.

Our invention relates to an improvement in apparatus for evaporating glue, the object being to provide means whereby a great portion of the water element in glue solutions may be eliminated therefrom with rapidity and with the application of heat for the shortest possible period, thereby avoiding the deteriorating 20 effects upon the glue of the long-continued application of heat.

With this object in view our invention consists in certain details of construction and combinations of parts, as will be hereinafter described, and pointed out in the claims.

In the accompanying drawings, Figure 1 is a view, in plan view, of our evaporating apparatus. Fig. 2 is a view in side elevation thereof. Fig. 3 is a view in section, showing the 30 feeding-tubes. Fig. 4 is a view, in longitudinal vertical section, of a modification of our apparatus. Fig. 5 is a view in vertical cross-section thereof. Fig. 6 is a view, in longitudinal cross-section, of a second modification; and 35 Fig. 7 is a view in vertical cross-section thereof.

A represents a helix of hollow copper tubing, mounted upon a reel, consisting of radial arms B, supporting longitudinal arms C. The radial arms B are attached to and radiate from 40 a steam-pipe, D, traversing the longitudinal axis of the helix, and have the arms C, which support the helix, secured to their outer extremities. The ends of the helix are attached to the steam-supply pipe D in such manner as 45 to establish open steam-communication between them.

In order to prevent the steam from passing directly through the pipe D and to fulfill the purposes of the invention, it is necessary to 50 divide the pipe D into two sections at a point between the points where the ends of the helix

are connected to it. The division of the pipe is practically accomplished by a plug, as at E, which will prevent the passage of the steam through the pipe and force it through the helix, 55 from which it will be discharged into the pipe in the form of waste steam and water in the opposite section thereof.

Inasmuch as in traversing the whole length of the helix the steam will become partially 60 condensed, it is necessary to supply live steam to the helix by arms F, which connect the pipe D with the helix A at different points thereof. In order, therefore, that the feeders F may be supplied with steam to conduct it to the helix 65 at different points of its length, it will be found necessary to plug the pipe D at a point near the point at which the discharging end of the helix is connected thereto. This will be obvious by reference to the drawings. Steam is 70 furnished to the pipe D from any convenient source through pipe G, provided with a packed joint, H.

The helix A, steam-pipe D, reel, and all subordinate accessories are mounted in a frame 75 adapted to be vertically reciprocated over a tank, I, containing a glue solution, which it is desired to reduce by the elimination of a portion of the water which it contains.

The frame above adverted to consists of horizontal beams J and vertical beams K. The outer ends of the beams J are pivoted at points exterior to the tank in such manner as to allow them a reciprocating vertical movement. The forward ends of the said beams J extend 80 over the tank I, containing the glue solution, and are provided with bearings L, in which the ends of the steam-pipe D are journaled, which latter has rotary movement imparted to it 85 through a pulley, M, mounted on one end of the said pipe and connecting by a belt, N, with a pulley, O, actuated by any convenient and suitable motor. Vertical beams K have their lower ends attached to the forward ends of the pivotal beams J, and have chains P or equivalent devices attached to their upper ends. Said chains P are adapted to be wound upon suitable drums or other devices, whereby they 95 may be raised and lowered to vary the depth, as may be required, to which the periphery of the helix A is immersed in the solution in the tank I.

Having set forth the construction of our evaporating apparatus, we will now proceed to briefly describe its method of operation.

Steam is admitted to pass through and heat the helix A, which is actuated in rotary motion with the pipe D, constituting its axis, by motion transmitted to pulley M through belt N from pulley O. The frame supporting the apparatus is now lowered through devices before explained until the periphery of the helix is immersed the required distance in the solution in the tank. As the helix revolves portions of the fluid solution will adhere to it and be separated from and elevated above the surface of fluid in the tank, to which it will be returned in a condensed state, falling thereinto in the shape of minute drops. Although the period of contact between the elevated portion of fluid and the helix is of but short duration, it is still sufficiently long to permit the heated tube to expel a great portion of the water in the fluid before it is returned to the mass in the tank. In falling back into the tank the liquid, being divided into minute drops, is cooled, and also further condensed and evaporated by exposure to the air. The rotary motion of the coil will establish a series of currents in the tank, which will operate to present every portion of the liquid to the helix. The revolving helix will, as thus explained, continually raise and heat new portions of the solution and expel the water therefrom in clouds of steam, while the partially-condensed drops of solution will constantly fall from the helix-coil into the tank in a shower of minute drops. As the expulsion of water from the fluid reduces it in bulk it is necessary during the evaporating operation to frequently lower the frame and helix by means of the adjustable chains before described, in order to keep the periphery of the helix immersed to the same depth in the liquid.

The result of the hereinabove-described method of applying heat to the surface of and momentarily heating a solution of glue is the rapid evaporation thereof without the danger of overheating attendant upon the old methods.

It is well known that the long-continued application of a low degree of heat or the application of a high degree of heat for a short period seriously impairs the adhesive qualities of glue or gelatine. The value of the latter for dietetic purposes is also affected.

Our invention contemplates only the momentary application of heat to the surface of the glue or gelatine, and is free from the objections above alluded to.

We have described and briefly outlined the manner of operation of the preferable form of apparatus necessary to carry out our invention; but it is apparent that such apparatus may assume different forms without transcending the scope of our invention.

Figs. 3, 4, 5, and 6, respectively, represent views in vertical longitudinal and vertical cross-sections of modified forms of apparatus.

In the modifications shown in Figs. 3 and 4, instead of disposing the heating-tubes in a helix, A, coiled on a reel, they are arranged in sections parallel with the central pipe, S, and have steam-communication therewith through radial arms A', which radiate from said pipe S like the spokes of a wheel. Each tube-section B' is supported at each end by an arm, A', as shown in the drawings. C represents a plug located at a suitable point within the pipe D to force the steam to take a prescribed course through the radial arms A' and tube-sections B'. The other accessories of this form of evaporator are substantially the same as those employed by the apparatus first described.

Figs. 5 and 6 represent still another form which our apparatus may assume and still fall within the scope of our invention. Herein parallel tubes A² connect in open steam-communication two annular chambers, each of which is formed by joining perforated segmental sections B², which do not communicate with each other. Each section B² of the chambers is connected by a pipe, C², with a steam-supply pipe, D², divided into as many compartments as there are chamber-sections. The necessity of such construction will be apparent, as each section of the chamber which communicates with a similar section of the other chamber by a number of hollow tubes A² must have independent entrance and exit for live steam, waste steam, and water. In this latter construction the steam-supply pipe D² is not continuous, but is simply secured to the outer face of each of the annular chambers, which are held in proper position by a solid shaft, E², interposed between their inner faces.

While it is apparent that our apparatus is adapted to the evaporation of all liquids, it is, as stated, chiefly intended to be used in the evaporation of glue and gelatinous solutions. To the latter use it has been found peculiarly adapted.

We would further have it understood that we do not limit ourselves to the exact constructions shown and described, but hold ourselves at liberty to make such slight alterations and variations in details of construction and combinations of parts as by fair intendment do not transcend the spirit of our invention.

Having fully described our invention, what we claim as new, and desire to secure by Letters Patent, is—

1. An evaporating apparatus consisting of a series of tubes disposed in cylindrical form, adapted to have steam passed through them, arranged to be raised and lowered over a tank containing the solution to immerse the tubes to different depths therein and to be revolved in contact with the surface of said solution, substantially as set forth.

2. An evaporating apparatus consisting of a helix or coil, each end of which communicates with a steam-pipe axially traversing it, a frame adapted to be vertically adjusted, and upon which the steam-pipe is journaled, and

- devices adapted to actuate the steam-pipe and helix in rotary motion, substantially as set forth.
3. An evaporating apparatus consisting, essentially, of a helix, each end of which communicates with a steam-pipe axially traversing it, said pipe being plugged between the points of helix communication to force the steam through the latter, feeding-arms radiating from the steam-pipe and connecting with and conducting steam to different portions of the helix, and a frame adapted to be vertically adjusted, upon which said steam-pipe is journaled to have rotary movement, substantially as set forth.
- 15 4. An evaporating apparatus consisting, essentially, of a helix wound on a reel mounted on a steam-pipe, which latter axially traverses the helix and with which its ends communicate, said pipe being plugged between the 20 points of helix communication to force the steam to take a prescribed path through the
- helix, steam-connection with one end of the steam-pipe, a pulley fixed to said pipe and connecting with motive power, and a frame, adapted to be vertically adjusted, upon which said pipe and accessories are journaled, substantially as set forth.
5. An evaporating apparatus consisting of a helix adapted to have steam passed through it, to be journaled upon a frame arranged to have vertical adjustment, and to be actuated in rotary movement with its periphery immersed in the solution to be evaporated, substantially as set forth.

In testimony that we claim the foregoing we 35 have hereunto set our hands this 24th day of March, 1881.
